United States Patent Office.

WILLIAM F. HOLSKE, OF NEW YORK, N. Y.

Letters Patent No. 77,285, dated April 28, 1868.

IMPROVED TUBULAR STRUCTURE.

The Schedule referred to in these Letters Patent and making part of the same.

TO ALL WHOM IT MAY CONCERN:

Be it known that I, WILLIAM F. HOLSKE, of New York, in the county and State of New York, have invented a new and useful Improvement in the Construction of Tubes and Barrels; and I do hereby declare that the following is a full, clear, and exact description thereof, which will enable those skilled in the art to make and use the same, reference being had to the accompanying plate of drawings, forming part of this specification.

Figure 1 is an end elevation of one of my improved tubes.

Figure 2 is a plan view of my improvement.

Figure 3 is an elevation of one of my improved binding-rings.

Figure 4 is an enlarged end elevation of one of my improved wedging or key-staves, and clamping-loop for operating the same.

Figure 5 is an enlarged sectional elevation of a portion of two of said key-staves and clamps.

Figure 6 is an enlarged view, in perspective, of a section of one of the binding-rings.

Similar letters of reference indicate corresponding parts.

The object of this improvement is to afford a convenient and economical method of constructing tubes and tubular structures, applicable for pneumatic railways, roadways of all kinds, water-conduits, gas-pipes, reservoirs for oil, and for conducting and containing solids, fluids, gases, and all kinds of substances.

The staves or body of the tubular structures made on this plan are intended to be composed of wood, but any other suitable substance or material may be employed. I do not limit or confine myself to any particular material for the manufacture of the staves or body.

Tubes and pipes made on my plan may be used either above or under ground or water.

To prevent decay, the wood should be treated with preservative substances before use.

Referring to the drawings, A are metallic binding-rings, between which the ends of the staves, or materials composing the body of the tube or structure, are held. The edges of the rings A are each provided with an annular recess or groove, a, as particularly shown in fig. 6, and the ends of the staves B are tongued to fit into the groove a, so that when put together, the sides of staves and the rings will be flush with each other. The edges of the staves are to be tongued and grooved.

Provision is made at suitable intervals for a break in the continuity of the annular grooves a, so that the staves may be conveniently introduced when setting up or building the tube. These breaks are illustrated at b, fig. 8, where the outer portion of the groove a is cut away, thus affording room for the introduction of the staves.

The staves and rings are bound together by means of screw-rods C and nuts c. The rods C pass through ears d', cast upon the rings A. When the staves have been introduced between the rings, the nuts c, upon the rods C, are tightly screwed up, and the staves and rings are thus tightly bound together in a longitudinal direction. Tubes of indefinite lengths may be thus constructed in a very expeditious and convenient manner.

In laying down a tube, it may readily be caused to deflect from a straight line, when desired, by making the staves longer upon one side of the tube than upon the other, as shown at x x' in the drawing.

In order to compress and hold the edges of the staves tightly together after they have been introduced into the grooves a, I make use of wedging or key-staves B', the sides of which are inclined, as particularly shown in fig. 4.

The wedging or key-staves B' are introduced at the breaks b, directly over which are located the clamping-loops D, which form part of the rings A. The key-staves B' are to be powerfully pressed downward by turning the clamping-screws d, one of which acts upon each end of the staves B'. The edges of the two staves B next adjoining the key-staves B' are to be bevelled like the edges of the staves B', so that when the latter are pressed down, the staves B will be pushed laterally, and firmly pressed together, (see fig. 4.)

Whenever it is desired to remove any or all of the staves B, it is only necessary to loosen the screws d.

W. F. HOLSKA.
